ABSTRACT OF THE DISCLOSURE

A toe-supporting device for use as a safety ski binding comprising a base plate which is secured to the ski and a toe jaw for holding the toe of a ski boot. The toe jaw is secured to the base plate by curved guide means for guiding the toe jaw so as to be pivotable in an arcuate direction about the center of curvature of the guide means. The center of curvature of the guide is located in front of the guide as seen in the longitudinal direction of the ski and is located outside and in front of the confines of the toe jaw. While pivoting to its releasing position, the toe jaw remains in engagement with and guides the boot and at first carries out only a movement in a substantially lateral direction for a predetermined distance prior to releasing the boot by movement in the forward direction. For this purpose, the arcuate guide is designed so that its center of curvature is spaced from the toe portion of the ski boot a distance which is equal to about three-quarters to one and one-half the width of the ski. The device further includes a releasable locking arrangement for normally maintaining the toe jaw in its central position on the ski. The two associated members of the locking device are preferably disposed slightly eccentrically to each other for the purpose of compensating for any play which might exist between the associated guide members of the arcuate guide.

The present invention relates to a toe supporting device for a safety ski binding which comprises a toe-clamping jaw which, when it is acted upon by strong lateral forces, is adapted to pivot from its normal position on the ski against a resilient force about an axis which is located in front of the toe portion of the foot and extends vertically to the upper surface of the ski.

If such a toe supporting device is of the conventional type in which the toe-clamping jaw (hereafter simply called the "toe jaw") is pivotally connected to a base plate on the upper surface of the ski by means of a pivot pin which is located underneath the toe jaw or within the confines thereof, the disadvantage occurs that, when in a fall of the skier the toe jaw is pivoted, for example, toward the right side from its normal position, the part of the toe jaw which engages upon the left side of the toe portion of the ski boot will describe an arc which, because of the relatively small turning radius of the toe jaw, is directed considerably toward the rear and will therefore also push the boot for a considerable distance toward the rear before it can disengage from the ski binding. This movement of the boot not only delays but also endangers the release of the boot from the ski binding.

It is an object of the present invention to provide a toe jaw for a safety ski binding which is designed and mounted in a manner so as to improve the safety of the ski binding and to insure especially in the event of a fall of the skier that his boot will quickly and automatically disengage from the binding.

2

Another object of the invention is to provide suitable guiding means of the most simple and inexpensive construction which in the event of a fall of the skier permit the toe jaw to pivot outwardly very easily and along a relatively large turning radius from its normal position on the ski, and which do not require any complicated guiding curves or complicated fitting work. More particularly, it is also an object of the invention to design these guiding means so as to permit the toe jaw when being released from its normal central position on the ski to carry out a pivoting movement which at first extends substantially in a lateral direction and thereafter continues in the form of a more sharply curved movement in the forward direction.

An important feature of the invention for attaining these objects consists in mounting the toe jaw on the ski, preferably on a support, for example, a base plate which is secured to the ski, so as to be movable along an arcuate guide, the center of curvature of which is located in front of the guide and more particularly at a point outside of the confines of the toe jaw.

The arcuate guide preferably forms a sector of a circle and its center of curvature is located substantially within the central longitudinal axis of the ski so as to permit the ski boot to disengage from the toe jaw equally well toward the right and toward the left of the ski.

The invention attains the advantage that the toe jaw, while pivoting to its releasing position remains in engagement with and guides the boot and at first carries out only a movement for a certain distance in a substantially lateral direction and thereafter carries out an increasing movement in the forward direction. For attaining this movement it has been found advisable to design the arcuate guide so that its center of curvature is spaced from the toe portion of the ski boot at a distance which is equal to approximately $\frac{3}{4}$ to $1\frac{1}{2}$ of the width of the ski, and preferably to the width of the ski. The advantageous result is hereby attained that during the pivoting movement of the toe jaw the supporting point of the boot on the toe jaw which is most remote from the side of the jaw toward which the jaw is pivoted will at first be moved only for a short distance toward the rear, while the supporting point of the boot nearest the opposite side of the toe jaw will carry out a relatively quick movement toward the front.

It is a further object of the invention to provide a very reliable and protected construction and arrangement of the associated members of the arcuate guide. Further features of the invention for attaining this object consist in securing the inner guide member which may be made of a substantially dovetailed cross section either to the ski or to the toe jaw. If this inner guide member is secured to the toe jaw, the particular advantage is attained that, when the toe jaw is pivoted toward one side or the other, the guide surfaces are not exposed toward the outside and are therefore better protected from being damaged. Another embodiment of the invention which is of particular advantage is one in which the guide member of the arcuate guide which is secured to the ski or to a base plate thereon only extends along the central part of the length of the associated guide member on the toe jaw when the latter is in its normal position, and in which the toe jaw is provided with lateral end walls which cover up and protect the first-mentioned guide member in lateral directions even when the toe jaw is pivoted fully outwardly. The associated members of the arcuate guide will thus be protected from being bent or damaged in any other manner even during the most severe falls of the skier.

Further objects of the invention are to provide suitable means for limiting the pivoting movement of the toe jaw and a releasable locking device for normally maintain-

ing the toe jaw in its central position on the ski. The two associated members of this locking device are preferably disposed slightly eccentrically to each other for the purpose of compensating for any play which might exist between the associated guide members of the arcuate guide.

These and other features of the present invention will become more clearly apparent from the following detailed description thereof which is to be read with reference to the accompanying drawings, in which:

FIGURE 1 shows a top view of one embodiment of the toe-supporting device according to the invention;

FIGURE 2 shows a cross section which is taken along the line 2—2 of FIGURE 1;

FIGURE 3 shows a cross section which is taken along the line 3—3 of FIGURE 1;

FIGURE 4 shows another top view of the device as shown in FIGURE 1, but with the toe jaw in the outwardly pivoted position;

FIGURE 5 shows a top view of another embodiment of the toe-supporting device according to the invention with the toe jaw in the outwardly pivoted position; while

FIGURE 6 shows a cross section which is taken along the line 6—6 of FIGURE 5.

As illustrated in FIGURES 1 to 4 of the drawings, the device according to the invention comprises a base plate 12 which is secured to the ski 10 by means of screws 11 and is covered with a sheet or coating 13 of a material with a low coefficient of friction, for example, a water-repellent plastic. On this sheet or coating 13, a guide member 14 of a dovetailed shape is secured to the base plate 12 by means of countersunk rivets 15 or the like. This guide member 14 has an arcuate shape and the center M of its curvature is located outside of the base plate 12 and substantially within the central vertical longitudinal plate of the ski. It is preferably made of light metal and has a central bore into which a metallic sleeve 16 is inserted the bore 17 of which serves as locking recess for receiving the locking member as subsequently described.

Guide member 14 guides the toe jaw 18 which is provided for this purpose with inwardly projecting parts 19 the walls of which surround the guide member 14 adjacent to the base plate 12 like a dovetail guide and form guide surfaces 20 which are in engagement with corresponding guide surfaces on guide member 14 so that the toe jaw 18 is movable along an arc about the center of curvature M in the direction of the arrows X₁ and X₂; as shown in FIGURE 1. This arcuate movement of the toe jaw 18 is limited by a stop pin 21 which is mounted on base plate 12 and engages into an arcuate groove 22 which is provided in the lower side of jaw 18. This groove 22 has the same center of curvature M as the guide member 14 and its opposite ends 22a and 22b are adapted to abut against the stop pin 21.

The toe jaw 18 also carries a sole holder 23 which is adapted to engage upon the upper side of the toe portion of the sole of the ski boot 24 and is adjustable by screws 25 to different heights from the upper surface of the ski 10.

The toe jaw 18 is normally held in its central position as illustrated in FIGURE 1 by a releasable locking device 26 which essentially consists of a locking member or ball 27 which is guided within a screwed-in bushing 29 and acted upon by a spring 28 which is inserted into and rests upon the bottom of a socket bore in a screw cap 30 which is screwed into the jaw 18 and locked thereto by a lock nut 31.

As shown in FIGURE 2, the axis of the guide bushing 29 and the center of the locking ball 27 of the locking device 26 are disposed slightly eccentrically at a distance e to the axis of the locking recess which is formed by the bore 17. This has the advantage that the locking ball 27 which is acted upon by the pressure of spring 28 tends to become centered in the bore 17 and thereby produces

a transverse force on the toe jaw 18 which acts in the longitudinal direction of the ski and compensates any play on the guide surfaces 20 between the guide member 14 on base plate 12 and the guiding parts 19 on the toe jaw 18.

5 The mode of operation of the device according to FIGURES 1 to 4 is as follows:

If a strong transverse force Q occurs on the boot 24, for example, because of a fall of the skier, this force causes the toe jaw 18 to swing against the resistance of the locking spring 28 in the outward direction, as indicated by the arrow X₁, about the center of curvature M. The supporting point A of the boot sole on the toe jaw 18 is thereby moved in an arcuate direction, as indicated by the arrow a, and the point A is thereby moved forwardly very quickly, while the supporting point B of the boot sole moves in the arcuate direction b. Although during this swinging movement the point B is also moved for a short distance h toward the rear, this distance is so small in accordance with the large turning radius r that it will not endanger or prevent the proper release of the boot.

Although by placing the center of curvature M still farther toward the front and by thereby increasing the turning radius r, this distance h may be even further reduced, this should not be done excessively since this would, in turn, decrease too much the forward displacement of the supporting point A so that the movement of the toe jaw would then almost amount to a parallel displacement of the two points A and B in the lateral direction which would interfere with the proper release of the boot. By calculation and tests it has been found that the most desirable releasing conditions will be attained if the radius r corresponds approximately to the width of the ski and may vary between a distance of 0.75 to 1.5 of this width.

FIGURE 4 illustrates the toe jaw 18 when pivoted as far as possible toward one side as determined by the engagement of the stop pin 21 with the end surface 22b of

40 groove 22.

FIGURES 5 and 6 illustrate a modification of the invention in which the toe jaw 18 is guided inversely to the manner as shown in FIGURES 1 to 4 insofar as the toe jaw 18 is provided with the inner guide member 32 of the arcuate guide and the base plate 12 is provided by means of rivets 33 with the outer guide member 34 which embraces the dovetailed projections 35 on the guide member 32 by means of its corresponding projections 36. The outer guide member 34 extends, however, only along a part f of the entire guide length, namely, only along that part which, when the toe jaw is fully pivoted toward the right, as shown in FIGURE 5, or toward the left, is still located underneath the toe jaw so that the guide surfaces 20 are fully protected from being damaged when the toe jaw is fully pivoted toward one side or the other. The toe jaw 18 is further provided with end walls 37 which close the ends of the recesses at both sides of the guide member 32 and also protect the arcuate guide at least at both sides of the toe jaw or in all directions when the toe jaw is in its central position. The parts of the arcuate guide are then fully encased in the upward, downward and lateral directions and thus protected from the entry of snow, ice, dirt or other foreign matter.

If the base plate 12 also of the device according to FIGURES 5 and 6 is covered with a sheet or coating 13 which consists of a water-repellent material with anti-friction properties, it is possible to reduce or eliminate entirely the danger that the contact surfaces of the movable toe jaw 18 and the base plate 12 might become covered with ice and freeze together.

Having thus fully disclosed our invention, what we claim is:

1. A toe-supporting device for a safety ski binding comprising a toe jaw for normally engaging upon the toe portion of a ski boot in the longitudinal direction of the

ski, and coacting first and second curved guide means for guiding the toe jaw during pivotable movement thereof in an arcuate direction about the center of curvature of said guide means, the center of curvature of said first and second curved guide means being disposed in front of said guide means as seen in the longitudinal direction of the ski and located outside and in front of the confines of said toe jaw, said first curved guide means being secured to the ski and the second curved guide means being secured to the toe jaw.

2. A toe-supporting device as defined in claim 1 wherein said first curved guide means comprises a first fitting secured to the ski and having formed thereon first guiding means of substantially dovetail cross-section shaped as a freely terminated segment of a circular free arc and said second guiding means is formed on said toe jaw of corresponding complementary dovetail cross section relative to said first guiding means and shaped as a freely terminated segment of a circular free arc, said first and second guiding means being intermeshed one within the other for slidably securing said toe jaw to said first fitting.

3. A toe-supporting device as defined in claim 2, in which said first guiding means comprises a ridge having a substantially dovetail-shaped cross section on said fitting disposed between a corresponding complementary dovetail-shaped grooved that comprises said second guiding means on said toe jaw.

4. A toe-supporting device as defined in claim 2, in which said second guiding means on said toe jaw comprises a ridge having a substantially dovetail-shaped cross section disposed between a corresponding complementary dovetail-shaped groove that comprises said first guiding means on said fitting, as seen in the longitudinal direction of the ski.

5. A toe-supporting device as defined in claim 2, in which said first guiding means on said fitting only extend along a central part of the arcuate length of said second guiding means on said toe jaw, and further comprising side walls on the ends of said second guiding means limiting the arcuate length thereof so that said toe jaw is pivotable in opposite arcuate directions from its central position until one of said side walls engages upon one of the ends of said first guiding means.

6. A toe-supporting device as defined in claim 2, further including locking means for normally maintaining said toe jaw in a central position on said ski, said locking means comprising a locking member moveably supported on said toe jaw, a bore formed on said first fitting, and resilient means for pressing said locking member at least partly into said bore with said toe jaw normally located in its central position.

7. A toe-supporting device as defined in claim 1, in which said first and second guide means have a circular curvature and said center of curvature is located at least closely adjacent to the central vertical longitudinal plane of the ski.

8. A toe-supporting device as defined in claim 1, further comprising means for limiting the extent of the pivotability of said toe jaw in either direction from its central position on said ski, said means for limiting the extent of the pivotability of said toe jaw relative to said

ski comprising an elongated arcuate recess formed on one of said parts, and a projection from the other of said parts extending into said recess and adapted to engage upon one of the ends of said recess upon said toe jaw being pivoted in one direction to the extent of pivotability desired.

9. A toe-supporting device as defined in claim 8, in which said elongated arcuate recess extends parallel to said curved guide means and opens in the downward direction, and said projection extends upwardly from said ski into said recess.

10. A toe-supporting device as defined in claim 1, in which said center of curvature is located at a distance of $\frac{3}{4}$ to $1\frac{1}{2}$ of the width of the ski in front of the points on said toe jaw adapted to engage with the toe portion of a ski boot.

11. A toe-supporting device for a safety ski binding comprising a toe jaw for normally engaging upon the toe portion of a ski boot in the longitudinal direction of the ski, and curved guide means for guiding the toe jaw so as to be pivotable in an arcuate direction about the center of curvature of said guide means, the center of curvature of said guide means being disposed in front of said guide means as seen in the longitudinal direction of the ski, said curved guide means comprising a first fitting secured to the ski and having formed thereon first guiding means, second guiding means formed on said toe jaw for guiding said toe jaw so as to be slidable along said first guiding means, at least one of said first and second guiding means being bent concavely toward the front, locking means for normally maintaining said toe jaw in a central position on said ski, said locking means comprising a locking member moveably supported on said toe jaw, a first bore formed on said first fitting, and resilient means for pressing said locking member at least partly into said first bore with said toe jaw located in its central position, said locking means further comprising guide means for said locking member, said locking member guide means having a guide bore containing said locking member and extending substantially vertically with respect to the upper surface of said ski, the axes of said guide bore and said first bore being parallel but offset with respect to each other by a fraction of the diameter of said first bore.
